United States Patent Office.

ELIZA JOYCE, OF NEW YORK, N. Y.

Letters Patent No. 83,638, dated November 3, 1868.

IMPROVEMENT IN LOW-WATER INDICATORS.

The Schedule referred to in these Letters Patent and making part of the same.

To all persons to whom these presents shall come:

Be it known that I, ELIZA JOYCE, now residing in the city, county, and State of New York, have made a new and useful invention to be applied to a Steam-Boiler for the purpose of giving notice or warning when the water thereof may become too low, or at a dangerous level therein; and I do hereby declare the same to be fully described in the following specification, and represented in the accompanying drawings, of which—

Figure 1 is a top view, and

Figure 2 an end elevation of it.

Figure 3 is a longitudinal section of its float-spindle and screw for fixing the apparatus to a boiler.

Figure 4 is a section of a boiler with the invention applied to it.

This invention is intended to be applied to a boiler, and at or about the level beyond which, for the purposes of safety, the water should not be suffered to fall therein, my invention being what may be termed "a low-water detector."

In the drawings, A denotes a screw, having a hole, a , bored through it longitudinally, such hole, at its inner end, being conical, or otherwise properly formed, as the seat for a valve, b, affixed to a spindle, B, which goes through the hole a , and is held in place therein by a washer or head, c, fixed on the spindle, near its outer end.

A crank or arm, d, extends from the inner end of the spindle, and supports a float, C, fixed firmly to it.

To the opposite end of the spindle, the elastic arm of a bell-hammer, D, is attached, and projected over a bell, E, and, with reference to the stops or studs f g , in manner as exhibited in the drawings.

One of the stops is projected from the head, h, of

the screw A, and the other from an arm, i, which is extended from the screw, and serves to support the bell E, which is connected to the arm by a screw or pin, k, arranged as represented.

The stops f g are to prevent the float from being depressed below the low-water level, or that of the spindle.

In applying the apparatus to a boiler, the screw A is to be screwed into the shell of the boiler at or about at the low-water level, the crank and the float being extended within the boiler.

As the hammer and the bell will be on the outside of the boiler, the water, in falling to a dangerous level, or into proximity therewith, will, when in ebullition, so vibrate the float as to cause the hammer to make a series of blows on the bell, and thereby give warning of the low state of the water. The position of the hammer will also serve to indicate the height of the water in the boiler.

One of the advantages of this apparatus over various other low-water detectors in which a float is a component part is, that its operation is not likely to be arrested by incrustations of saline or other matters.

I claim the arrangement, in connection with the boiler, of the float C and alarm E, directly connected together by the crank-spindle B, substantially as described, so that the ebullition of the water, when at a determined level in the boiler, will effect the vibration of the float, and the consequent sounding of the alarm, as set forth.

E. JOYCE.
